UNITED STATES PATENT OFFICE.

ROBERT E. KIRSCH, OF MILWAUKEE, WISCONSIN.

MULTIPLE-SEAT UNIT.

1,209,452.

Specification of Letters Patent. Patented Dec. 19, 1916.

Application filed January 22, 1916. Serial No. 73,519.

To all whom it may concern:

Be it known that I, ROBERT E. KIRSCH, a citizen of the United States, and resident of Milwaukee, in the county of Milwaukee and State of Wisconsin, have invented certain new and useful Improvements in Multiple-Seat Units; and I do hereby declare that the following is a full, clear, and exact description thereof.

10 The present invention relates to new and useful improvements in seat structures and is more particularly directed to the provision of a structure wherein a plurality of seat portions are combined in a single unit, 15 to thus reduce the essential number of supporting legs, whereby a structure is provided which is relatively simple and which permits ready cleaning therearound by means of a broom or the like.

20 It is in general the object of the present invention to simplify and otherwise improve the construction of structures of this character, and it is more particularly an object to provide such a structure which may 25 be very readily assembled to adapt it for use as a knock-down or portable structure if so desired.

It is further an object to embody the foregoing features in a folding seat structure 30 wherein the assembled relation of various supporting parts holds the seats for proper pivotal movements.

With the above and other objects and advantages in view, the invention resides more 35 particularly in the novel combination, arrangement and formation of parts more particularly hereinafter described and particularly pointed out in the appended claims.

In the drawings, Figure 1 is a vertical 40 transverse sectional view through a chair seat unit constructed in accordance with the present invention, this view being taken on the line 1—1 of Fig. 2; Fig. 2 is a front elevational view of a seat unit, with parts 45 broken away to more clearly disclose the pivot mounting of the seats.

Referring now more particularly to the accompanying drawings, there is provided a pair of end supports preferably comprising 50 each a quadrantal frame 5 at the upper corner of which is provided a pair of spaced arms 5' between which the body bar 6 of the seat unit is secured as by the bolts 6', the bar seating on the frame to relieve strain 55 on the bolts. This body bar is rectangular in cross-section and is formed in channel

shape to provide a relatively large cross-section facilitating attachment of the seat carrying bars 7. These bars are secured to the body bar by spaced depending arms 8 60 at their forward ends adapted to embrace the bar, and bolts 9 are passed through the arms and body bar. The seat bars extend rearwardly from the body bar, and their rear ends are upwardly directed at 10 and coact 65 to carry a plurality of back panels 11 therebetween. To provide arm rests, bars 12 extend forwardly from the upwardly directed portions 10 of the seat bars and are supported at their forward ends by braces 13 70 connected with the forward body bar portions. Each seat bar and its associated arms 8, bar 12 and brace 13 preferably comprise an integral structure.

The seats proper are preferably each 75 formed of a plate 14 of material braced at its side edges by angle irons 15 and each seat proper is pivotally mounted between a respective pair of seat bars by pivot shafts 16 which are loose in pivot openings 17 80 formed in the intermediate seat bar portions and which have reduced ends engaged in respective pivot openings 18 of the single irons 15.

The pivot shafts are disposed in their 85 respective pivot openings as the seat carrying bars 7 are assembled and are held against displacement by the shoulders formed by their reduced ends. It is thus noted that the bolts 6' and 9 form the only 90 means for holding the entire structure assembled, and thus a ready assembly and disassembly of the structure may be had, to adapt it as a portable or knock-down structure if so desired. 95

It is noted that the body bar 6 forms the forward support for the seat angle irons 15, and that the various strains incident to persons' weights on the seats are so distributed that strain on the securing bolts is 100 obviated whereby they serve merely to hold various parts against displacement, and thus a structure of maximum strength is procured.

I claim:

1. A seat structure comprising a body bar, members extending laterally in spaced relation from said bar, back portions carried by said members, and seat portions pivotally carried by said members and adapted to 110 rest on the body bar.

2. A seat structure comprising a chan-

neled body bar, members extending laterally therefrom and including portions embracing and seating on said bar, and seat and back portions carried by said members.

5 3. A seat structure comprising a body bar, members extending laterally therefrom and provided with pivot openings, seat portions provided at their sides with pivot openings, pivot shafts disposed in the openings of the said members, and reduced ex-

tensions at the ends of the shafts engaging in the openings of the seat portions.

In testimony that I claim the foregoing I have hereunto set my hand at Milwaukee, in the county of Milwaukee and State of 15 Wisconsin, in the presence of two witnesses.

ROBERT E. KIRSCH.

Witnesses:

GEO. W. YOUNG,
M. E. DOWNEY.
